IGNITION ANALYZER METER

John V. Vachtel, Los Angeles, Calif., assignor to Rite
Autotronics Corporation, Los Angeles, Calif.

Filed June 13, 1973, Ser. No. 369,542

Term of patent 14 years

Int. Cl. D10—04

U.S. Cl. D10—78

Fig. 1.

Fig. 2.

Fig. 3.

Fig. 5.

Fig. 4.

FIG. 1 is a right side elevational view of an ignition analyzer meter showing my new design, the left side being a mirror image thereto;

FIG. 2 is a front elevational view thereof;

FIG. 3 is a top plan view thereof;

FIG. 4 is a bottom plan view thereof; and

FIG. 5 is a rear elevational view thereof.

I claim:

The ornamental design for an ignition analyzer meter, as shown and described.
